CLAIM

The ornamental design for a face mask extender, as shown and described.

DESCRIPTION

FIG. 1 is a perspective view of the face mask extender.

FIG. 2 is front view thereof.

FIG. 3 is a back perspective view thereof.

FIG. 4 is left side view thereof.

(Continued)

FIG. 5 is right side view thereof.

FIG. 6 is top view thereof; and,

FIG. 7 is bottom view thereof.

The broken lines showing the equidistantly aligned, circular features with an inner ornament, as shown in FIGS. 1 and 2 illustrate environmental features that form no part of the claimed design.

1 Claim, 3 Drawing Sheets
